UNITED STATES PATENT OFFICE.

CLARENCE S. JACKSON, OF BROOKLYN, NEW YORK.

CLOSURE FOR TUBES.

1,314,065.

Specification of Letters Patent. Patented Aug. 26, 1919.

Application filed May 22, 1918. Serial No. 235,996.

To all whom it may concern:

Be it known that I, CLARENCE S. JACKSON, a citizen of the United States, and a resident of the borough of Brooklyn, county of

5 Kings, city and State of New York, have invented certain new and useful Improvements in Closures for Tubes, (Case A,) of which the following is a specification.

One important object of the invention is 10 to provide a closure device for collapsible tubes, such as are used to hold and dispense tooth paste, shaving cream and the like, which embodies novel features of construction whereby the closure can be removed 15 from the discharge orifice of the tube by a mere pull thereon and replaced by a simple push, thus eliminating the tedious and troublesome unscrewing and screwing of a cap and the possibility of sticking of the 20 cap or the stripping of the threads.

Another important object of the invention is to provide a closure for collapsible tubes of the class described which will be always positively connected to the tube whether in 25 position to close the discharge orifice or removed therefrom, whereby the loss of the closure by laying the same down or accidentally dropping it into the drain pipe of a wash stand or the like, is prevented.

30 A further object of the invention is to provide a closure of the character described which is in the nature of a plug or slip cover, and which embodies a construction whereby it can be readily adapted for use 35 upon the conventional screw-threaded nozzles of collapsible tubes without modification of the said nozzles, and whereby a circular discharge orifice in a nozzle can be converted into a rectangular orifice to discharge the contents of the tube in the form 40 of a ribbon as is often desirable.

Another object of the invention is to provide a closure device for collapsible tubes which is strictly sanitary, and comparatively 45 simple and inexpensive in its construction, which features are especially necessary in containers designed for dispensing tooth paste and shaving cream.

With these and other objects in view 50 which will more fully appear as the description proceeds and the nature of the invention is better understood, the invention consists in certain novel constructions, combination and arrangement of the parts as will 55 be more fully pointed out in the following description and appended claims.

For a full understanding of the invention reference is to be had to the following description and accompanying drawing in which:

60 Figure 1 is an enlarged perspective view of the discharge end of a collapsible tube provided with an exteriorly screw-threaded discharge nozzle, showing an adapter cap and closure device embodying the invention 65 applied thereto, the closure device being in an open position;

Fig. 2 a vertical longitudinal sectional view through the same with the closure device in a closed position;

70 Fig. 3 a transverse vertical sectional view through the discharge nozzle and closure device;

Fig. 4 an enlarged perspective view of the 75 discharge end of a collapsible tube provided with a discharge nozzle of a modified construction having the closure device embodying the invention applied directly thereto, the closure being shown in an open position;

Fig. 5 a side elevation thereof with the closure in a closed position;

Fig. 6 a vertical longitudinal sectional view through the same;

Fig. 7 a transverse vertical sectional view 85 through the nozzle and closure;

Fig. 8 a side elevation of a modified form of the closure member;

Fig. 9 a vertical longitudinal sectional view through the same;

Fig. 10 a view similar to Fig. 9, showing 90 the closure member applied to an adapter cap which is applied to a conventional threaded nozzle as illustrated in Figs. 1 to 3, inclusive; and

Fig. 11 a detached perspective view of the adapter cap shown in Fig. 10.

Corresponding and like parts are referred to in the following description and indicated in all the views of the drawing by the same 100 reference characters.

Referring in detail to Figs. 1 to 3, inclusive, of the drawings, the reference character A designates a collapsible tube of a conventional construction, provided with a 105 cylindrical discharge nozzle a, which is exteriorly threaded at b, and is formed with a circular discharge orifice c.

An interiorly threaded adapter cap 20 is 110 designed to be screwed upon the nozzle a, said cap being provided in the top thereof with a discharge orifice 21. In the present

2

instance this discharge orifice 21 is rectangular in shape, and of a length substantially the same as the diameter of the discharge orifice *c* of the nozzle *a*. It thus will be seen that when the adapter cap 20 is screwed upon the nozzle it serves to convert the circular discharge orifice *c* into a rectangular orifice so that the contents of the tube A will be discharged in the form of a ribbon.

10 A packing disk 22 of any suitable material, such as cork, is interposed and clamped between the cap 20 and the edges of the nozzle so as to prevent escape of the contents of the tube between the cap and orifice. This packing disk 22 is provided with a centrally disposed opening 23 of a size slightly less than and a shape substantially the same as the discharge orifice 21 of the cap, said opening being adapted to register with the discharge orifice 21 with the edges thereof slightly overlapping the edges of the orifice 21. The sides of the cap 20 are formed with a pair of diametrically opposite longitudinally extending grooves 24 which are closed at their ends by the curved shoulders 25, said grooves serving as guideways for and coöperating with the closure device B to secure the closure to the cap 20.

The closure device B comprises a substantially U-shaped yoke or frame 1 which is formed of a single strip of spring sheet material which has its ends 2 bent at substantially right angles to the body portion 3 thereof, the ends 2 being parallel and serving as spring supporting arms for the closure device, and having a length substantially equal to the height of the adapter cap 20. The body portion 3 is of a length substantially the same as the diameter of the cap 20.

40 The yoke or frame member 1 is adapted to be applied to the cap 20 with the arms 2 thereof straddling the cap and frictionally engaging the sides thereof, as indicated in Figs. 1 and 2. The arms 2 are provided near their outer ends with spring lugs or tongues 4 which are preferably stamped therefrom and project into and engage the grooves 24 in the sides of the cap 20 to secure the yoke or frame 1 to the cap.

50 This frame 1 serves as a support for and carries a closure plug 7, the frame being provided, at the junction of each of the arms 2 and body portion 3 and on the inner sides of the arms, with a crimp or groove 5, said crimps or grooves being adapted to receive and frictionally engage the flanges 6 of the closure plug 7 and also serving as finger holds for operating the closure. This closure plug is formed of any suitable frictional material which will not oxidize or decompose, and is provided with a reduced tongue or rib 8 which is of a shape and size adapted to snugly fit into and frictionally engage the inner walls of the discharge orifice 21 of the cap so as to tightly seal the

same. The tongue 8 of the plug is also adapted to pass through the opening 23 of the packing disk 22, and this opening being slightly smaller than the discharge orifice 21 of the cap and the packing disk being formed of a resilient material the opening 23 of the disk will be stretched as the plug is inserted, and the edges of the opening 23 in the packing disk will be held in a snug engagement with the tongue 8 of the plug by the elasticity of the disk so as to insure the sealing of the discharge orifice 21 of the cap.

The plug 7 is applied to the frame 1 by merely forcibly sliding the end flanges 6 thereof into the crimps 5 of the frame 1, and the plug is securely held in this position by frictional engagement of the flanges 6 thereof with the crimps 5. The frame 1 being of spring material, the crimps will be resilient so as to spring against the flanges 6 to increase the friction.

In order to tightly close the discharge orifice 21 the tongue or rib 8 of the closure plug 7 is forced inwardly into the discharge orifice, as shown by Figs. 2 and 3, and in this position the flanges 6 of the plug 7 engage the top of the cap 20 and completely cover the edges of the discharge orifice 21 so as to positively prevent escape of the contents of the tube A and to exclude dirt. To remove the plug 7 from the discharge orifice the frame 1 is grasped between the forefinger and thumb, the crimps 5 serving as finger holds, and the whole frame pulled directly outward until the tongues 4 engage the curved shoulders 25 at the outer ends of the grooves 24 in the cap 20, which limit the outward movement of the frame 1 on the cap. The frame 1 is then swung to either side of the cap 20, the tongues 4 and shoulders 25 serving as a pivot, as indicated by dot-and-dash lines in Fig. 3. The closure device B is thus swung away from the discharge orifice to allow free discharge of the contents of the tube, but the closure is always positively held in engagement with the cap by the tongues 4 in the grooves 24, so that loss or misplacing of the closure is precluded. It is also impossible for the closure to come into contact with a wash stand, as is frequently the case with separately constructed and detachable closures such as screw caps, and contamination of or injury to the closure is thus prevented. When in an operative or closed position the closure is prevented from displacement laterally of the nozzle by the plug 7 and tongues 4, and the plug is held against accidental withdrawal from the discharge orifice 21 by the frictional engagement of the arms 2 and sides of the cap.

To positively hold the closure B against accidental movement longitudinally of the cap 20, the cap may be provided with sockets or depressions 26 in the bases of the grooves 24, into which the spring tongues 4 will snap

when the closure is pushed into a closed position. With this construction a deliberate pull on the frame 1 of the closure would be necessary to withdraw the plug 7 from the discharge orifice 21.

5 The invention also contemplates the attachment of the closure device B directly to the discharge nozzle of a collapsible tube, thus eliminating the adapter cap. One possible construction for this purpose is illustrated by Figs. 4 to 7 inclusive of the drawings. The collapsible tube A is provided with a nozzle a' of a modified construction, said nozzle comprising the comparatively 10 broad side walls b' and narrow end walls c' , the said walls forming a substantially rectangular discharge orifice d . The end walls c' are each provided with an external longitudinally extending groove e which 15 is closed at its outer end by the curved shoulder f , and at its inner end by the top of the tube. These grooves e correspond with the grooves 24 in the adapter cap 20 shown in Fig. 1, and are adapted to coöperate 20 in a similar manner with the tongues 4 of the arms 2 of the closure device B. The operation of the closure on this modified nozzle a' is the same as upon the adapter cap 20, the plug 7 being adapted to 25 snugly fit into and frictionally engage the walls of the discharge orifice d to seal the same, and the flanges 6 of the closure plug engaging the edges of the nozzles a' when 30 in a closed position, exactly as they engage 35 the top of the adapter cap. To lock the closure member in a closed position on the nozzle a' the bases of the grooves e may be provided with sockets or recesses 9 adapted to coöperate with the tongues 4 of 40 the closure member frame, exactly as the recesses 26 in the adapter cap 20 coöperate with the tongues 4.

A slight modification of the closure device is illustrated in Figs. 8 and 9, in which longitudinal slots 10 are formed in the supporting arms 11 of the closure C, said slots being adapted to coöperate with studs 12 formed integrally with the end walls of the nozzle a' . The slots 10 perform the 45 function of the guide grooves 24 above described, while the studs 12 serve the same purpose as the tongues 4. The construction of the closure C is otherwise identical with that of the closure B, and the operation 50 of both closures is the same. Further description of the closure C is thus deemed unnecessary.

The closure C can be also adapted for use in connection with conventional externally threaded discharge nozzles such as the nozzle a previously described, by the use of an adapter cap provided with projecting studs, instead of grooves as is the adapter cap 20. As indicated in Figs. 10 55 and 11, the adapter cap 30 is identical in

construction with the cap 20, except that it is provided with a pair of diametrically opposite outwardly projecting studs 31 adapted to coöperate with the slots 10 in the arms 11 of the closure C, in a manner 70 similar to that in which the studs 12 coöperate with the closure C, instead of the grooves 24 of the cap 20. This cap 30 is screwed upon the nozzle a of the tube A exactly as the cap 20 is screwed on the nozzle 75 a' , and the operation of the closure device C in this case is similar to the operation of the closure C on the nozzle a' , so that further description is deemed unnecessary.

From the foregoing it will be obvious 80 that the closure is extremely simple and inexpensive, yet being a great and much desired, if not necessary, improvement upon the usual cap closures which are both inconvenient and unsanitary. The adapter 85 cap serves to convert a circular discharge orifice into a rectangular orifice to discharge the contents of a tube in the form of a ribbon, at the same time serving to carry a plug closure and adapt the same for 90 use upon conventional exteriorly threaded discharge nozzles without modification of the nozzle, the closure being always positively connected to the nozzle. Further, it is to be noted that the closure is easily 95 detachable from the nozzle of the tube or the cap 20, by simply springing the arms 2 or 11 away from the ends of the nozzle or sides of the cap 20 to clear the tongues 4 from the grooves e or 24, or the slots 10 100 from the studs 12 or 31, and that the closure is thus interchangeable with any one of all tubes having nozzles or caps constructed as above described. The plug 7 is extremely 105 sanitary and is removably mounted in the frame 1 so as to be easily replaced if mutilated or soiled.

What I claim is:—

1. A closure for collapsible tubes including a substantially U-shaped closure frame 110 member, said frame member comprising a body portion and a plurality of arms projecting at an angle from said body portion, the said frame member being provided at the junction of the arms and body portion with 115 inwardly facing opposed and laterally extending grooves opening through one edge of each of the arms, and a closure member provided with outwardly projecting flanges mounted in said frame member, the said 120 flanges of the closure member being slideable into and frictionally held within the said grooves in the frame member.

2. A closure for collapsible tubes including a substantially U-shaped closure frame 125 member comprising a body portion and a spring arm projecting at substantially right angles from each end thereof, said arms being adapted to straddle the discharge nozzle and frictionally engage the walls 130

thereof, and said frame member being provided at the junction of the body portion and arms thereof with opposed inwardly facing and laterally extending grooves 5 which open through one edge of the arms of the frame, a closure member mounted in said frame member and provided with outwardly projecting flanges adapted to slide into and be frictionally held within 10 said grooves, said closure member being adapted to close the discharge orifice of the collapsible tube, and means for positively connecting said frame member to the discharge nozzle whereby the frame is capable 15 of movement relatively to the nozzle.

3. A closure for collapsible tubes including a closure frame member formed of a single strip of spring sheet material and comprising a body portion having a spring 20 arm bent at substantially right angles to each end thereof, said spring arms being adapted to straddle the discharge nozzle of a collapsible tube, and the frame member being provided at the junctions of the body 25 portion and spring arms with inwardly facing opposed and laterally extending crimps opening through one side of the arms of the frame, said crimps projecting outwardly beyond the ends of the body portion 30 and the outer faces of the spring arms to form finger holds for manipulation of the frame member, and a closure member mounted in said frame and provided with outwardly projecting flanges adapted to 35 slide between the arms of the frame into and be frictionally held within said crimps, said closure member being adapted to close the discharge orifice of the collapsible tube.

4. The combination with a collapsible 40 tube having a cylindrical exteriorly threaded discharge nozzle provided with a discharge orifice which is circular in transverse section, of an interiorly threaded cap adapted to be screwed upon said discharge nozzle, said cap being provided with a rectangularly shaped discharge orifice to cause the contents of the tube to be discharged in the form of a ribbon, a closure member adapted to close said discharge orifice of the cap, 45 and means for positively locking said closure member to the cap to allow movement of the closure relatively to said cap and to limit said movement.

5. A closure for collapsible tubes includ-

ing a cap adapted to be secured upon the discharge nozzle of a collapsible tube, said cap being provided with a discharge orifice, an elastic packing disk clamped between said cap and nozzle and provided with an opening slightly smaller than the discharge orifice of the cap and adapted to register therewith, and a closure plug adapted to be inserted through the discharge orifice of the cap and the opening in the packing disk to seal the said discharge orifice. 65

6. The combination of a collapsible tube having a discharge nozzle provided with a discharge orifice circular in transverse section, of a cap adapted to be secured on said discharge nozzle, said cap being provided 70 with a rectangularly shaped discharge orifice to cause the contents of the tube to be discharged in the form of a ribbon, a closure member adapted to close said discharge orifice of the cap, and means for locking said 75 closure member to the cap to allow a limited movement of the closure relatively to the said cap.

7. The combination of a collapsible tube having a discharge nozzle provided with a discharge orifice circular in transverse section, of a cap adapted to be secured on said discharge nozzle, said cap being provided with a rectangularly shaped discharge orifice to cause the contents of the tube to be 80 discharged in the form of a ribbon, a closure member provided with a rectangular plug adapted to enter and close the said rectangular discharge orifice and to lock the closure to the cap against independent rotation, and 85 means for positively connecting said closure member to the cap to allow a limited relative longitudinal movement of the closure on the cap. 90

8. The combination of a collapsible tube 95 having a discharge nozzle provided with a discharge orifice, of a cap adapted to be secured on said discharge nozzle, said cap being provided with a discharge orifice smaller in transverse section than the discharge orifice of the nozzle, a closure member adapted to close said discharge orifice of the cap, and means for locking said closure member to the cap to allow a limited movement of the closure relatively to the said cap. 100 105

This specification signed this seventh day of March, A. D. 1918.

CLARENCE S. JACKSON.
